(57) **CLAIM**

An ornamental design for an iced beverage maker, as shown and described.

DESCRIPTION

FIG. 1 is a perspective view of an iced beverage maker showing our new design;

FIG. 2 is a front elevational view thereof, all sides being the same;

FIG. 3 is a top plan view thereof;

FIG. 4 is a bottom plan view thereof;

FIG. 5 is an exploded perspective view thereof;

FIG. 6 is a front elevational view of FIG. 5;

FIG. 7 is a top plan view of FIG. 5;

FIG. 8 is a bottom plan view of FIG. 5; and,

FIG. 9 is a perspective view of an iced beverage maker showing a second embodiment of our new design.
